UNITED STATES PATENT OFFICE.

EUGENE ANTZ, OF HOMESTEAD, OREGON.

CURRENT-MOTOR.

1,371,836.

Specification of Letters Patent. Patented Mar. 15, 1921.

Application filed October 21, 1919. Serial No. 332,277.

To all whom it may concern:

Be it known that I, EUGENE ANTZ, a citizen of the United States, residing at Homestead, in the county of Baker and State of Oregon, have invented certain new and useful Improvements in Current-Motors, of which the following is a specification.

This invention has for its object to provide a current motor embodying such features of improvement as tend to increase the power and efficiency of motors of this type.

Another object is the provision of an efficient type of rotor and anchoring means therefor, whereby the rotor is caused to assume an oblique position with relation to the direction of flow of the stream upon application of a load thereto, thus securing maximum efficiency of the motor in operation.

With these and other objects in view as will appear as the description proceeds the invention comprises the novel features of construction combination of elements and arrangement of parts which will be more fully described in the following specification and set forth with particularity in the claims appended hereto.

Figure 1 represents a plan view of the improved motor applied to use.

Fig. 2 represents a similar view showing a modified position of the rotor.

Fig. 3 is a plan view of the motor illustrating a modified type of anchoring means.

Fig. 4 represents a detail of one of the floats.

Fig. 5 represents a fragmental side elevation of the combined anchoring and power transmitting means disclosed in the modification illustrated in Fig. 3.

Referring to the drawing in detail, wherein similar reference numerals designate corresponding parts throughout the several views, the numeral 5 indicates the shaft of the rotor which is preferably of hollow form as illustrated in Fig. 4 to increase the buoyancy thereof and assist in maintaining the rotor in a predetermined position with relation to the surface of the stream 6. Floats 8 of hollow form provided with sleeves 8^a are secured adjacent the opposite terminals of the shaft 5 and are of hollow cylindrical form to support the shaft, as desired, upon the surface of the stream, or in partially or entirely submerged position according to

the degree of buoyancy of the floats 8 which may be conveniently varied by admitting water to the internal chambers of the floats.

For convenience in admitting water to the floats, the latter are provided with valved inlet ports 9 which may be conveniently opened to admit the desired quantity of water to the float and subsequently closed to render the float airtight. In order to reduce friction due to the rotary movement of the shaft 5 to the lowest possible degree, the shaft is preferably journaled for rotation within the floats 8 and is provided with collars 8^b thus permitting the floats to remain substantially stationary, with relation to the rotary movement of the shaft during operation of the motor. When found necessary, due to the length of the shaft 5 additional floats 10 may be located intermediate the ends thereof and, as is clearly evident, these floats constitute floating bearings in which the shaft is rotatably supported upon a body of water.

A plurality of current operated vanes or blades 11 are secured upon the shaft 5 and are arranged in spaced relation to provide passages between them for the flow of water. The several blades or vanes 11 have a corresponding spiral curvature and due to the spacing of the blades longitudinally of the shaft 5 adequate space is provided between them for the passage of water.

A buoyant support in the form of a barge or other craft 12 is provided with bearings 13 in which the anchored terminal of the shaft 5 is journaled and suitable gearing, flexible shaft or other adequate power transmitting means is connected with this terminal of the shaft whereby the rotary movement thereof is transmitted to any desired point remote therefrom. An anchoring cable 13^a is connected with one terminal of the floating support 12 and is adequately secured at its opposite terminal to the bank 7 of the stream. A ring is swivelly mounted upon the opposite terminal of the shaft 5 and is connected with a restraining cable 14 also anchoring upon the shore or bank 7 whereby the outward movement of the shaft with relation thereto is limited.

It has been found by practical experiment, that maximum efficiency of the motor is obtained when the spiral blades 11 are maintained in a position in a substantially two-thirds submerged position although it will

be clearly apparent that the position of the blades and shaft may be readily varied as preference or conditions may dictate by varying the quantity of the liquid contents of the several floats 9 and 10. The pitch of the spiral blades or vanes 11 is such that when there is resistance to the rotary movement of the shaft 5, as when a load is applied thereto, the pressure exerted by the current against the obliquely disposed submerged portions of the blades exerts a tendency to move the shaft to an oblique position, with relation to the direction of flow of the stream, as suggested in Fig. 1.

15. The cable 14 acts as a restrainer for limiting the outward swinging movement of the shaft 5 so as to maintain the shaft in such angular position as to secure maximum efficiency and the utilization of the pressure exerted by the current of the stream in producing rotary movement of the rotor. The cable 14 further prevents the shaft from moving outwardly to such position that the submerged portions of the spiral blades lie 25 substantially parallel to the direction of the current as, obviously, in this position the pressure of the current on opposite sides of the blades is equal and tendency to rotate the shaft thus counteracted.

30. As suggested in Fig. 2, the position of the rotor may be reversed so that the outer terminal of the shaft is disposed up stream. When the position of the rotor is thus changed, it is evident that the direction of 35 rotation of the shaft is reversed, provided the direction of flow of the stream remains the same that the possibility of reversing the position of the rotor is particularly desirable to cope with local current conditions. 40. For instance, under normal conditions the rotor may be maintained in the position shown in Fig. 1 when the current is flowing in the direction of the arrow in that figure. However when the direction of the 45 current changes and is opposite to that indicated by the arrow in Figs. 1 and 2, as during the rise of the tide, the position of the rotor may be changed to that shown in

Fig. 2 without changing the direction of rotation thereof.

50. In the modification of the invention illustrated in Fig. 3, the rotor which is designated generally by the numeral 5 is provided with the usual shaft having connection with a shaft section 20 which is connected to the shaft of the rotor by a universal joint 21. The opposite terminal of the shaft section 20 is connected with a driven shaft 22 by a universal joint 23. The driven shaft 22 is adequately supported in 55 bearings 24 which may be conveniently located upon the shore or bank of the stream and due to the provision of the two universal joints 21 and 23 it is evident that the position of the floating shaft 5 may be varied according to variations in the level of 60 the surface of the stream.

65. What I claim is:

1. A current motor comprising a hollow shaft, buoyant supporting means having 70 bearings thereon at one end of the shaft, a plurality of equally spaced current operated blades rotatable with said hollow shaft, a plurality of hollow floats supporting said hollow shaft and anchoring cables connecting the buoyant supporting means and the end of the shaft to the shore to limit its movement with the current of the stream.

75. 2. A current motor comprising a hollow shaft, buoyant supporting means having 80 bearings thereon rotatably supporting one end of the shaft, a plurality of spaced, current operated screw blades rotatable with said hollow shaft, a plurality of hollow floats supporting said hollow shaft and constituting bearings for said hollow shaft, valved inlet ports for admitting water to the hollow floats to limit the depth of the 85 shaft and blades, and anchoring cables on the end of the shaft and buoyant supporting 90 means for restraining the movement thereof with the current of the stream.

95. In testimony whereof, I affix my signature hereto.

EUGENE ANTZ.
